ABSTRACT OF THE DISCLOSURE

A continuous process for the purification of light paraffinic fraction boiling in the range of 25° to 100° C. and containing as major portion straight chain paraffins, branched paraffins and cycloparaffins and as a minor portion an impurity selected from the group consisting of aromatic hydrocarbons, sulphur-containing compounds, nitrogen-containing compounds, and other non-hydrocarbon impurities, and mixtures thereof, the sulphur content being no greater than 500 p.p.m., said process comprising:

hydrogenating said light paraffinic fraction at a temperature in the range of 150 to 375° C., under a partial pressure of hydrogen of 10 to 100 kg./cm.², at a space velocity of 0.5 to 20 v.v./h. and a hydrogen to hydrocarbon ratio of 100 to 3,000 Nm.³/m.³, in the presence of a hydrogenating catalyst containing between 0.1 and 2% of platinum on a silica-alumina carrier, silica being in major quantity, and at least 30% of the platinum being distributed on the catalyst surface which is accessible to the reactants, fractionating the products of the hydrogenation to separate the hydrogenated sulphur- and nitrogen-containing compounds and to recover a paraffinic fraction substantially containing only paraffinic hydrocarbons with an increased content of cycloparaffins.

This invention relates to a process for the purification of light paraffinic petroleum distillates. More particularly, the present invention relates to a process for the purification of light paraffinic distillates comprised mainly of paraffinic hydrocarbons containing from 5 to 7 carbon atoms.

In the distillation of naphtha fractions of petroleum, frequently there is produced a light paraffinic fraction comprising primarily C₅—C₇ paraffinic hydrocarbons and containing a minor amount of aromatic hydrocarbons, sulphur-containing compounds, nitrogen-containing compounds and other impurities. These paraffinic hydrocarbons include straight-chain compounds, branched compounds and cycloparaffins.

For many uses, these light paraffinic fractions must be practically free from aromatic hydrocarbons and other impurities, namely sulphur-containing compounds. In particular, the use of unleaded gasoline results in an increasing demand for branched paraffinic hydrocarbons, some of these compounds having a particularly high octane number. Therefore, it is desirable to isomerize the straight chain paraffins of these light paraffinic fractions or, at least, to increase the content of branched paraffins in these fractions. However, with many isomerization processes, the content of aromatic hydrocarbons and sulphur-containing compounds in the feeds isomerized is of great importance. Many isomerization catalysts are very sensitive to these impurities, which must be removed as completely as possible. The known methods for refining light paraffinic hydrocarbons generally require special techniques, such as a two-step pretreatment comprising the

2

hydrodesulphurization of the feed and then the hydrogenation of any unsaturated hydrocarbons. Such processing is expensive.

An object of the present invention is to provide a process for the treatment of light paraffinic fractions in order to remove simultaneously the aromatic hydrocarbons and the sulphur-containing compounds. Another object of this invention is to provide a process whereby this treatment is performed with reduced investments and operating costs.

According to the present invention, there is provided a continuous process for the purification of a light paraffinic fraction boiling in the range of 25° to 100° C. and containing straight-chain paraffins, branched paraffins and cycloparaffins with a lower content of aromatic hydrocarbons, sulphur-containing compounds, nitrogen-containing compounds and other impurities, the sulphur content being preferably not greater than 500 p.p.m., said process comprising

subjecting said paraffinic fraction to hydrogenation at a temperature in the range of 150 to 375° C., under a partial pressure of hydrogen of 10 to 100 kg./cm.², at a space velocity of 0.5 to 20 v.v./h. and a hydrogen to hydrocarbon ratio of 100 to 3,000 Nm.³/m.³, in the presence of a hydrogenating catalyst containing between 0.1 and 2% by weight of platinum on a silica-alumina carriers, silica being in major quantity, and at least 30% of the platinum being distributed on the catalyst surface which is accessible to the reactants, fractionating the products of said hydrogenation to separate the hydrogenated sulphur- and nitrogen-containing compounds and to recover a paraffinic fraction substantially containing only paraffinic hydrocarbons with an increased content of cycloparaffins.

Several methods are known for the hydrogenation of petroleum fractions containing aromatic hydrocarbons, particularly for the hydrogenation of kerosene and fuels, in order to improve their combustion value. But these methods most frequently relate to the treatment of fractions boiling in the range of 60° to 350° C., to reduce their content of aromatic hydrocarbons. However, the hydrogenation yield is generally not higher than 98%, this yield being nevertheless more than enough to increase the combustion value of these fractions.

By contrast, the process of the present invention is applied to lighter fractions and it must perform to practically completely remove the aromatic hydrocarbons and also the sulphur-containing compounds. Therefore the present process differs from the prior processes in that a specific feed is treated in the presence of a specific catalyst in order to obtain a product which must have specified properties.

The feed to the present process mainly comprises paraffinic hydrocarbons containing from 5 to 7 carbon atoms inclusive, more generally 5 to 6 carbon atoms, the amount of straight-chain paraffins being at least 30% and more often at least 50% by weight. The feed contains also branched paraffins and cycloparaffins. The amount of aromatic hydrocarbons, more particularly benzene and toluene, may be present within wide limits, but generally is present in an amount within the range of 0.1 and 10% by weight.

The amount of sulphur-containing compounds present in the feed to the process of the present invention generally is between about 50 and 500 p.p.m. If the amount is higher, the paraffinic fraction is advantageously desulphurized prior to use in the present process. This desulphurization treatment need not be directed in such a manner as to secure a complete removal of the sulphur-containing compounds as required with prior processes.

A caustic wash will likely suffice. Another means of such desulphurization comprises subjecting said petroleum cut to a sweetening treatment to convert mercaptans contained in said cut into heavier disulphides so that a subsequent distillation gives a paraffinic fraction with a low sulphur content. The object of these desulphurizing treatments is only to reduce the sulphur content of the paraffinic fraction to a level lower than about 500 p.p.m. The prior processes generally require a complete removal of the sulphur-containing compounds before hydrogenation of the paraffinic fraction and therefore, are more expensive.

In accordance with the process of the present invention, the light paraffinic fraction is hydrogenated under the above specified conditions, preferably, however, hydrogenation is carried out at a temperature within the range of 175° to 325° C., under a partial pressure of hydrogen of between about 15 to 75 kg./cm.² and with a space velocity from 0.5 to 20. The optimum conditions depend not only on the composition of the paraffinic fraction and on its content of aromatic hydrocarbons, cycloparaffinic hydrocarbons and sulphur-containing compounds, but they depend also on each other. Therefore, the temperature to be applied for a substantially complete removal of the aromatic hydrocarbons varies as a function of the sulphur content of the feed, the other conditions remaining equal. Also, the temperature may be lowered when the pressure is higher. Determination of such optimum value within the above defined ranges may readily be made by those skilled in the art.

In order to economically perform, a substantially complete hydrogenation of the aromatic hydrocarbons and of the sulphur-containing compounds, the hydrogenating catalyst will contain from 0.1 to 2% by weight of platinum on a silica-alumina carrier, where silica is in major quantity and where at least 30% of the platinum is distributed on the catalyst surface which is accessible to the reactants. Indeed, it has been found that with catalysts, whose carrier does not contain a greater amount of silica than alumina or whose platinum is poorly distributed on the surface, the degree of aromatic hydrogenation is lower under the conditions which prevail than with the catalyst utilized in the present invention.

Many processes are known for the manufacture of catalysts containing platinum on a carrier. However, a convenient process for preparing the present catalyst comprises impregnating the silica-alumina carrier with a solution of a platinum compound, usually chloroplatinic acid and then evaporating the solution and thereafter drying and calcinating the catalyst at about 400° C. Impregnation of the carrier may be performed with solutions of water soluble platinum salts, but with the use of solutions having a pH from about 1 to 7. An extended drying and a moderate calcination of the catalyst are particularly suitable. Under these conditions, at least 30% of the platinum is distributed on the total surface of the catalyst which is accessible to the reactants. Determination of this percentage of platinum on the surface is carried out by using described methods, e.g. the method of D. E. Mears and R. C. Hansford, in *Journal of Catalysis*, vol. 9, pp. 125-127 (1967).

In order to illustrate the effect of the catalyst composition, comparative hydrogenation tests were carried out on a light paraffinic fraction having the following composition:

	Percent (by weight)
n-Pentane	61.0
Iso-pentane	13.8
Cyclopentane	4.7
2,2-dimethylbutane	0.6
2,3-dimethylbutane	0.4
2-methylpentane	3.5
3-methylpentane	3.3
n-Hexane	8.2
Methylcyclopentane	3.0

Percent (by weight)

Cyclohexane	0.7
Benzene	0.7
Sulphur, 200 p.p.m.	

5 The operating conditions for hydrogenation were the following:

temperature: 290° C.
partial pressure of hydrogen: 70 kg./cm.²
space velocity: 2 v./v./h.
hydrogen:hydrocarbon ratio: 500 Nm³/m.³ (500 m.³ of liquid feed at 0° C. and 760 mm. Hg per m.³ of liquid feed at 15° C.)

15 The catalyst used in each test consisted of platinum on a silica-alumina carrier. However, the ratios of silica, alumina and platinum were different in each test. The catalyst compositions and the results of these tests are summarized in Table I.

TABLE I

Test number	Weight percent				
	Silica in carrier	Pt of catalyst	On surface	Residual benzene	Residual S (p.p.m.)
25 1	16.2	0.73	52	72	2
2	68.7	0.74	61	0.3	1
3	68.6	0.68	42	0.4	1
4	83.9	0.76	15	56	8
5	68.7	0.08	54	62	13

30 Results presented in the above Table I clearly demonstrate that the catalyst must fulfill all of the above specified conditions relating to platinum content, the platinum distribution on the surface of the catalyst and composition of the carrier, in order to obtain a substantially complete aromatic hydrogenation of the light paraffinic fraction. Tests 2 and 3 show that the hydrogenation yield is higher than 99.5%. By contrast, a catalyst carrier which has a lower content in silica (test 1) does not perform an adequate hydrogenation, although the content and the distribution of the platinum are substantially the same as those of the catalysts of tests 2 and 3. The same appears with a catalyst having a poor distribution of the platinum (test 4) or with a catalyst having a low content in platinum (test 5).

45 46 Other hydrogenation tests were carried out in order to show the effect of temperature on the removal of aromatic hydrocarbons. In these tests, the catalyst contained 0.72% by weight of platinum on a silica-alumina carrier with 83.8% of silica. The amount of platinum 50 distributed on the accessible surface of this catalyst was 43%.

The composition of the used light paraffinic fraction hydrogenated was as follows:

	Percent by weight
n-Pentane	92
Iso-pentane	1.7
2,2-dimethylbutane	0.3
2,3-dimethylbutane	
Cyclopentane	1.5
2-methylpentane	
Methylcyclopentane	traces
Cyclohexane	3.5
Benzene	1.0

65 66 The sulphur content was varied during some of the tests by adding dimethyldisulfide.

The operating conditions for hydrogenation were as follows:

70 71 partial pressure of hydrogen: 50 kg./cm.²
space velocity: 2 v./v./h.
hydrogen:feed ratio: 500 Nm³/m.³

75 The sulphur content of the feed and the temperature employed in each test and the results are summarized in Table II.

TABLE II

S content of feed	Tempera-ture (° C.)	Residual benzene (p.p.m.)
50 p.p.m.	250	45
	270	7
	290	5.5
	310	9
100 p.p.m.	250	200
	270	35
	290	18
	310	12
	330	30

These results show that the hydrogenation of the aromatic hydrocarbons is greater when the sulphur content of the feed is lower. They also show that the hydrogenation of aromatics is greatly influenced by reaction temperature.

The aromatic hydrogenation is favored by an increase of the partial pressure of hydrogen, but reaction temperature remains an important factor. Table III gives the results of tests which were carried out at a space velocity of 2, starting from a light paraffinic feed containing 100 p.p.m. of sulphur, but at different pressures and temperatures.

TABLE III

Partial pressure of hydrogen (kg./cm. ²)	Tempera-ture (° C.)	Residual benzene (p.p.m.)
50	250	200
	270	35
	290	18
	300	12
	310	11
	320	16
	330	16
70	250	120
	270	13
	290	5
	300	4
	310	6
	330	7

During the hydrogenation of the aromatic hydrocarbons contained in the light paraffinic fraction in accordance with the present invention, the sulphur-containing compounds are converted into H₂S which is easily removed by distillation. Isomerization of some paraffinic compounds occurs also during this hydrogenating treatment. These advantages of this invention are shown by the results presented in Table IV of a test for the hydrogenation of a light paraffinic fraction under the following conditions:

temperature: 330° C.

partial pressure of hydrogen: 50 kg./cm.²

space velocity: 2 v./v./h.

hydrogen/hydrocarbons ratio: 500 Nm.³/m.³

The hydrogenated products were distilled to remove H₂S formed during the hydrogenation.

TABLE IV

Compounds	Feed	Hydrogen-ated product
n-Pentane, percent by wt.	95.2	86.1
Iso-pentane	.1	.9
Dimethylbutanes	.5	.5
Methylcyclopentane	Traces	3.2
Cyclohexane	3.3	1.1
Benzene, p.p.m.	1.9	31
Sulphur, p.p.m.	100	1

¹ Or 9,000 p.p.m.

The above mentioned tests show that the aromatic hydrocarbons of a light paraffinic fraction may be hydrogenated with a practically quantitative yield. The best results are obtained when the sulphur content of the feed is not higher than 100 p.p.m. In such instance, the hydrogenation preferably is carried out at a temperature between 275° and 330° C. and under a partial pressure of hydrogen varying between about 50 and 70 kg./cm.² and with the hydrogenation yield higher than 99.5%. The sulphur-containing compounds are simultaneously converted into H₂S, which is easily distilled off, so that the end product is practically sulphur-free.

The results of Table IV show also that during this hydrogenation of the light paraffinic hydrocarbon, an isomerization occurs with a yield which is about 12% under the conditions employed in the example. This yield may be increased by operating at a higher temperature. However, the temperature is kept within the above stated limits in order to secure a practically complete hydrogenation of the aromatic hydrocarbons.

For carrying out the subsequent isomerization of the paraffinic fraction, it is essential that the hydrogenated fraction does not contain more than 100 p.p.m. of residual aromatics and not more than 30 p.p.m. of sulphur, in order to prevent rapid deactivation of the isomerization catalyst. These conditions are easily fulfilled by applying the process of this invention.

From the foregoing description, one skilled in the art can easily select the optimum operating conditions which are the most convenient for a specific feed for the purpose of reducing the aromatic content below about 10 p.p.m. and the sulphur content below about 5 p.p.m.

What is claimed is:

1. A continuous process for the purification of light paraffinic fraction boiling in the range of 25° to 100° C. and containing as a major portion straight chain paraffins, branched paraffins and cycloparaffins and as a minor portion an impurity selected from the group consisting of aromatic hydrocarbons, sulphur-containing compounds, nitrogen-containing compounds, and other non-hydrocarbon impurities, and mixtures thereof, the aromatic hydrocarbon content being between 0.1 and 10% by weight the sulphur content being no greater than 500 p.p.m. said process comprising:

hydrogenating said light paraffinic fraction at a temperature in the range of 150 to 375° C., under a partial pressure of hydrogen of 10 to 100 kg./cm.², at a space velocity of 0.5 to 20 v./v./h. and a hydrogen to hydrocarbon ratio of 100 to 3,000 Nm.³/m.³, in the presence of a hydrogenating catalyst consisting essentially of between 0.1 and 2% of platinum on a silica-alumina carrier, silica being in major quantity, and at least 30% of the platinum being distributed on the catalyst surface which is accessible to the reactants,

fractionating the products of the hydrogenation to separate the hydrogenated sulfur- and nitrogen-containing compounds and to recover a paraffinic fraction substantially containing only paraffinic hydrocarbons with an increased content of cycloparaffins, less than 100 p.p.m. aromatic hydrocarbons and less than 30 p.p.m. sulphur.

2. The process of claim 1 wherein the hydrogenation reaction is carried out at a temperature of between 175° and 325° C., under a partial pressure of hydrogen of between 15 and 75 kg./cm.² and with a space velocity of 0.5 to 20 v./v./h.

3. The process of Claim 1 wherein said light paraffinic fraction comprises one containing paraffinic hydrocarbons of 5 to 7 carbon atoms.

4. The process of Claim 1 wherein said light paraffinic fraction contains no greater than 10% aromatic hydrocarbons by weight.

5. The process of Claim 1 wherein said light paraffinic fraction contains at least 30% straight chain paraffin hydrocarbons.
